A. A. STOLLE.

ELECTRIC RAILWAY.

(Application filed Oct. 22, 1901.)

(No Model.)

UNITED STATES PATENT OFFICE.

ALBERT A. STOLLE, OF NEW YORK, N. Y.

ELECTRIC RAILWAY.

SPECIFICATION forming part of Letters Patent No. 699,590, dated May 6, 1902.

Application filed October 22, 1901. Serial No. 79,512. (No model.)

To all whom it may concern:

Be it known that I, ALBERT A. STOLLE, a citizen of the United States, residing in the borough of Manhattan, city, county, and State 5 of New York, have invented certain new and useful Improvements in Electric Railways, of which the following is a specification.

In electric railways built according to the underground-trolley systems at present in use 10 there is always a gap in the conductors at points where two lines cross each other. The cars are carried across these gaps by starting some distance back of the gap and acquiring sufficient momentum to go across, the car- 15 switch being then turned off, so that the car is carried across by a flying start. This is objectionable for several reasons. At night the break in the current causes the lights in the car to go out. Much time is also lost in 20 practically stopping the car some distance before getting to the crossing and then having to wait until the street is clear to go across with a great speed. It is difficult to remedy this matter. The contact-shoes of the plows 25 now in common use cannot well be made longer because of the difficulty which would be met with in going around curves.

According to my invention I provide an improvement whereby a gap in a conductor such 30 as described though normally open to permit the passage of a crossing car may be closed upon the approach of a car or during the passage of a car across such gap, so as to avoid the disadvantages above pointed out.

35 My invention provides also mechanism having various other features of advantage, as specified hereinafter in detail.

Referring to the accompanying drawings, illustrating embodiments of my invention, 40 Figure 1 is a plan, partly in section, of a system of conductors of the type common in underground-trolley roads to which one form of my improvement is applied. Fig. 2 is a side elevation of Fig. 1. Fig. 3 is an end elevation 45 thereof. Fig. 4 is a section on the line 44 of Fig. 1. Figs. 5 and 6 are details of the hook shown in Fig. 1. Fig. 7 is a horizontal section of a modified form of hook.

50 My invention provides means for closing a gap, as above explained, which comprises a movable bridge-piece and means for moving the same into position to form a connection

across said gap, so that a car may continue its movement as if there were no gap at all. Preferably the movement of the bridge-piece 55 is automatic, taking place just as a car is passing over the gap or just previous to such passage of a car. Preferably, also, the operation of the bridge-piece is accomplished by a member fixed to the car—such, for example, 60 as the contact member or shoe of the plow now ordinarily in use. After the passage of the car across the gap the bridge-piece may be automatically returned to its original position. The bridge-piece which I provide may 65 alone entirely close the gap by forming a complete connection between the parts of the conductor on opposite sides of the gap, or my invention embraces equally a construction in which the gap is reduced to such a size that 70 the contact member carried by the car may itself complete the circuit between the two parts of the conductor. The construction and arrangement of the bridge-piece may also be varied considerably as well as the mechanism 75 for operating the same.

Referring to the particular embodiment of my invention illustrated in the drawings, A represents a conductor which may consist of an ordinary T-bar having a vertical side 80 face adapted to receive a contact member from the car and which is in two parts separated by a gap at the point where similar conductors of a crossing line meet it. The supports for the conductor, as well as the adjacent parts of the conduit in which it is ordinarily carried, are omitted for the sake of clearness. The bridge-piece for bridging this gap is preferably a straight strip B, of any suitable conducting material, which extends 90 backward some distance from the gap, as shown in dotted lines in Fig. 1, and the rear portion of which is slidably connected on one part of the conductor A—as, for example, by flanged antifriction guide-rollers C, running 95 on the upper and lower edges of the conductor A. The bridge-piece is held normally away from the gap, so as to permit the passage of a crossing car, preferably by means of a weight, such as D, moving up and down 100 in a pit E in the center of the conduit and connected by a chain F with the rear end of the bridge-piece. In systems employing a pair of opposite conductors A and A', Fig. 1,

one carrying the outgoing and the other the return current, I use two bridge-pieces B, preferably connecting them at the rear end by a depressed cross-piece G, to the center 5 of which the weight D may be attached. I preferably also provide means for limiting the backward movement of the bridge-piece, which means may consist of a projection H, adapted to engage a fixed stop J, adjustably 10 connected to the conductor A, as shown.

The means for engagement of the car with the bridge-piece is a projecting member, preferably a hook, attached directly to the bridge-piece in position to be engaged by the 15 contact-shoe carried by the car, so that as the contact member crosses the gap it remains in engagement with the bridge-piece, carrying the latter along with it, and thus continues in connection with the conductor. It 20 is advisable to arrange this hook so that it shall not only be automatically engaged by the shoe of a car moving in the usual direction and shall be automatically released from such shoe after it has served its purpose in bridging the gap in the conductor until the shoe 25 passes across the gap, but also it should be arranged to be automatically withdrawn from the path of a car moving in the opposite direction, as it is sometimes necessary even 30 in double-track roads for cars to move backward. Such a hook is shown at K, and may be connected to the bridge-piece B in any suitable manner. As shown, the hook K is, 35 Fig. 6, rigidly fastened to a shaft L, vertically arranged in bearings M at a point preferably intermediate the ends of the bridge-piece and near to its forward end. The hook K is normally pressed back into a recess N of the bridge-piece by means of a spring O, which 40 bears against an arm P, Fig. 5, which has a shoulder bearing against a pin Q on the shaft L, so that as the arm P is pressed outward by the spring O the hook K is pressed inward, bringing the parts normally in the dotted-line 45 position at the right of the gap in Fig. 1. When the shoe R, moving to the left in Fig. 1, strikes the arm P, the inward pressure on this arm forces out the hook K, which catches onto the front end of the shoe, whereby the 50 bridge-piece is carried with the shoe across the gap. For forcing the hook K out as the arm P is pressed inward there is preferably a spring connection between the two, such as the spring S, which normally holds the arm 55 P in the position shown in Fig. 5 with respect to the shaft L of the hook, but permits the arm P to be moved inward against the pressure of the spring S if there is any resistance to outward movement of the hook K. The 60 groove T in the hub of the arm P permits the necessary movement of the shaft L. This function is especially useful in the case of a shoe moving in the backward direction. The shoe will strike the arm P and press it inward 65 before it has entirely passed the hook K, so that both the hook K and the arm P will be pressed inward at the same time and the spring

S will yield accordingly. I may provide also an automatic means for withdrawing the hook K from the shoe of a forwardly-moving car 70 after the gap has been bridged. For this purpose the shaft L may be provided with an arm U, preferably at its lower end, and extending under the conductor A. The conductor is then provided with a downwardly-extending stop V, located at a suitable point 75 thereon and extending into the path of the arm U, so that as the arm U strikes the stop V the shaft L is turned until the hook K is withdrawn within the face of the bridge-piece 80 B and out of engagement with the shoe. The shoe then passes on and the weight D automatically withdraws the bridge-piece to its normal position, leaving the gap clear for the passing of crossing cars. With the form of 85 hook shown it is necessary to cut out the conductors A at the points indicated, as shown best in Fig. 4.

A different form of hook which may serve the same purpose as that above described is 90 shown in Fig. 7. In this case the hook K' is normally held in position to be engaged by the contact-shoe R, the chain F of the retracting-weight being directly connected to an arm P' of the hook for this purpose. A shoe moving in the backward direction strikes the inclined forward face of the hook and throws it backward far enough to permit the passage of the shoe, the shoe being mounted to yield also laterally. The arm U and stop V for 95 withdrawing the hook from engagement with the shoe may be the same as for the hook shown in Fig. 1. With either of the forms of hook shown it is preferable to have the ends 100 of the bridge-piece B beveled, so that the contact member of the car shall shift easily from the conductor A to the bridge-piece B. It is not essential, however, that the hook or other engaging means be at the forward or at an intermediate point of the bridge-piece, as it 105 may be at the rear end and still be within my invention.

The operation of the separate elements of the device having been described, the operation of the whole will be clear. As the car 115 moves in the direction from right to left in Fig. 1 its contact-shoe first rides up on the beveled end of the bridge-piece B and slides along the bridge-piece until it strikes the arm P of the hook, which throws out the hook K 120 and engages the shoe. The continued movement of the shoe carries the bridge-piece B across the gap, remaining of course in contact with it until it has entirely crossed the gap, when the hook is released by the action 125 of the arm U on the stop V and the shoe rides over the forward end of the bridge-piece and onto the conductor. The weight D then acts to pull the bridge-piece back to its normal position. In case a car moves backward the 130 shoe rides up on the forward beveled end of the bridge-piece. The hook K is normally out of its path, but it strikes the arm P, which yields against the force of the springs

O and S. The shoe then rides all the way along the bridge-piece B and back at its rear end onto the conductor A.

The arrangement shown is suitable for a double-track system, in which cars normally move always in the same direction. By omitting the weight D, however, and making the bridge-piece B symmetrical at opposite ends—that is, providing it with oppositely-arranged hooks and with guide-rollers at both ends—it may be adapted for a single track, in which case cars moving in opposite directions on the same track transfer the bridge-piece alternately from one side to the other of the gap.

Though I have described with great particularity of detail specific embodiments of my invention, yet it is to be understood that I am not limited to the specific forms shown and described; but that various modifications of the details and arrangements of the parts may be made by those skilled in the art of electric railways without departure from my invention.

I claim as my invention—

1. In an electric-railway crossing, the combination with a conductor of one line having a vertical side face adapted to receive a contact member and having a gap at the point where it crosses the other line, of means for closing said gap including a movable bridge-piece supported upon one part of said conductor, extending along the vertical contact-face thereof, and having a similar side contact-face and means for moving the same into or out of position to form a connection across said gap.

2. In an electric-railway crossing, the combination with a conductor of one line having a vertical side face adapted to receive a contact member and having a gap at the point where it crosses the other line, of means for closing said gap including a movable bridge-piece supported upon one part of said conductor, extending along the vertical contact-face thereof and having a similar side contact-face and means automatically moving the same into or out of position to form a connection across said gap as a car passes over said crossing.

3. In an electric-railway crossing, the combination with a conductor of one line having a gap at the point where it crosses the other line, of means for closing said gap including a movable bridge-piece slidably connected to said conductor at one side of said gap, and means automatically moving the same into position to form a connection across said gap as a car passes over said crossing, and means for automatically returning said bridge-piece to its original position.

4. In an electric-railway crossing, the combination with a conductor of one line having a gap at the point where it crosses the other line, of means for closing said gap including a movable bridge-piece slidably connected to said conductor at one side of said gap, and means attached directly to the bridge-piece in

position to be engaged by the contact member of a car for moving said bridge-piece with said contact member to continue the connection of said contact member with the conductor as said contact member crosses said gap.

5. In an electric-railway crossing, the combination with a conductor of one line having a gap at the point where it crosses the other line, of means for closing said gap including a movable bridge-piece slidably connected to said conductor at one side of said gap, and means attached directly to said bridge-piece in position to be engaged by a car for moving said bridge-piece to a position to form a connection across said gap as a car passes over said crossing, and means for automatically returning said bridge-piece to its original position.

6. In an electric-railway crossing, the combination with a conductor of one line having a gap at the point where it crosses the other line, of means for closing said gap including a movable bridge-piece slidably connected to said conductor at one side of said gap, and means connected to said bridge-piece adapted to be engaged by a car for moving said bridge-piece to a position to form a connection across said gap as a car passes over said crossing, means for automatically disengaging said bridge-piece when the car has passed said crossing, and means for automatically returning said bridge-piece to its original position.

7. In electric railways, means for closing a gap in a conductor comprising a movable bridge-piece, a projecting member connected to said bridge-piece, and means whereby said projecting member is automatically engaged by a car moving in one direction and withdrawn from the path of a car moving in the opposite direction.

8. In electric railways, means for closing a gap in a conductor comprising a movable bridge-piece, a hook connected to said bridge-piece, and means whereby said hook is automatically engaged by a car moving in one direction and withdrawn from the path of a car moving in the opposite direction.

9. In electric railways, the combination with a conductor A adapted to receive a contact member on its vertical side face and formed in two parts separated by a gap, of a bridge-piece supported upon one part of said conductor extending along the vertical contact-face thereof and adapted to be moved in a direction to close said gap.

10. In electric railways, the combination with a conductor A adapted to receive a contact member on its vertical side face and formed in two parts separated by a gap, of a bridge-piece supported slidably upon one of said parts extending along the vertical contact-face thereof and adapted to be slid across said gap to close the same.

11. In electric railways, the combination with a pair of opposite conductors A A' each adapted to receive a contact member on its vertical side face and formed in two parts

separated by a gap, of a bridge-piece supported upon one part of said conductors extending along the vertical contact-faces thereof and adapted to be moved in a direction to close said gaps.

12. In an electric-railway crossing, the combination with a pair of conductors of one line having vertical side faces between and in contact with which the contact member of the car travels and which have gaps at the point where they cross the other line, of means for closing said gaps including a movable bridge-

piece supported upon said conductors, extending along the vertical contact-faces thereof and having similar side contact-faces and means for moving the same into or out of position to form connections across said gaps.

In witness whereof I have hereunto signed my name in the presence of two subscribing witnesses.

ALBERT A. STOLLE.
